* cited by examiner

Primary Examiner—Raphael Barkai*Assistant Examiner*—Randall H. Gholson(74) *Attorney, Agent, or Firm*—Welsh & Katz(57) **CLAIM**

The eyeglasses, as shown and described.

DESCRIPTION

FIG. 1 is a perspective view of the eyeglasses of the claimed design;

FIG. 2 is a top view of the eyeglasses of FIG. 1 of the claimed design;

FIG. 3 is a front elevational view of the eyeglasses of FIG. 1 of the claimed design;

FIG. 4 is a side elevational view of the eyeglasses of FIG. 1 of the claimed design;

FIG. 5 is a bottom view of the eyeglasses of FIG. 1 of the claimed design;

FIG. 6 is a rear elevational view of the eyeglasses of FIG. 1 of the claimed design; and,

FIG. 7 is a perspective view of the eyeglasses of FIG. 1 of the claimed design shown in a folded orientation.

The broken line showing of the lenses is for illustrative purposes only and forms no part of the claimed design.
